PISTON RING

Carl F. Engelhardt, Yeadon, Pa., assignor to
Wilkening Manufacturing Company, Philadelphia, Pa., a corporation of Delaware

Application October 21, 1940, Serial No. 362,120

6 Claims. (CL. 309—45)

The present invention relates to a self-expanding piston ring and it relates more particularly to a self-expanding piston ring which is preferably made of sheet metal, and so formed, constructed, and arranged as to present two relatively narrow parallel annular cylinder-contacting sealing surfaces composed of a multiplicity of sector-like sections disposed end to end in close proximity to each other so as to constitute more or less continuous annular cylinder-contacting surfaces with but a very small gap between the sectors, and spring means forming an integral part of the piston ring and also preferably formed of the same sheet metal of which the cylinder-contacting elements are formed, thereby to tend to expand the ring tangentially or circumferentially with a resultant radially outward expansion of the component cylinder-contacting elements thereof.

The present application is a continuation-in-part of applicant's co-pending application Serial No. 321,200, filed February 28, 1940.

The piston ring of the present invention may be used both for oil control purposes in the bottom ring-receiving groove of a piston which has apertures through the piston wall for oil drainage and which may also be used in the upper ring-receiving grooves without any oil drain holes through the piston wall, for compression purposes.

For the purpose of illustrating the invention, there are shown in the accompanying drawings forms thereof which are at present preferred, since the same have been found in practice to give satisfactory and reliable results, although it is to be understood that the various instrumentalities of which the invention consists can be variously arranged and organized and that the invention is not limited to the precise arrangement and organization of the instrumentalities as herein shown and described.

In the accompanying drawings in which like reference characters indicate like parts,

Figure 1 represents a top plan view of a piston ring embodying the present invention, as shown installed in a piston disposed within a cylinder, which is generally on line 1—1 of Figure, 3 (the parts not being in true proportion, for purposes of better illustration).

Figure 2 is a perspective view of a fragmentary portion of the piston ring of the present invention on a much enlarged scale, showing the construction of the radially-inwardly-extending spring loops.

Figure 2—A represents a perspective view of 55

the fragmentary portion of the piston ring of Figure 2 but showing the construction of the outer periphery of the ring.

Figure 3 represents a section on line 3—3 of 5 Figure 2.

Figure 4 represents a section on line 4—4 of Figure 2.

Figure 5 represents a sectional view of the upper portion of a piston showing the piston ring of the present invention, disposed in each of the three ring-receiving grooves thereof.

Figure 6 represents a perspective view of a fragmentary portion of a sheet metal blank in its flat condition of which the piston ring of the present invention may be formed, but before the cylinder-contacting elements 22 and 23 have been bent over and before the spring-forming elements 25 have been formed or shaped into the springs 51 intervening the cylinder-contacting elements 22 and 23.

Figures 7 and 8 represent a front view and a top elevational view, respectively, of a fragmentary portion of a strip of piston ring material like that shown in Figure 6, but after the cylinder-contacting elements 22 and 23 have been bent over and after the intervening spring-forming portions 25 have been formed into the generally U-shaped springs 51, but before the strip has been completely formed into the arcuate formation by the further collapsing of the U-shaped spring members 51.

Figures 9 and 10 represent a front elevational view and a top plan view, respectively, similar to that shown in Figures 7 and 8, but after the strip had been formed into generally arcuate form corresponding generally to the curvature of the cylinder in which the piston ring is to be used, by further collapsing the generally U-shaped spring members 51 and by bringing the juxtaposed radial edges 44 and 45 of the cylinder-contacting elements 22 and 23 into close proximity to each other.

Figure 11 represents a perspective view, similar to that of Figure 6, showing a sheet metal blank for the formation of another embodiment of the present invention.

Figure 12 represents a perspective view similar to that of Figure 2 of the embodiment indicated in Figure 11.

Figure 13 represents a perspective view similar to that of Figure 6, showing a sheet metal blank for the formation of still another embodiment of the present invention.

Figure 14 represents a perspective view sim-

ilar to that of Figure 2 of the embodiment indicated in Figure 13.

Figure 15 represents a perspective view, similar to that of Figure 6 showing a sheet metal blank for the formation of another embodiment of the present invention.

Figure 16 represents a perspective view similar to that of Figure 2 of the embodiment indicated in Figure 15.

Figure 17 represents a perspective view similar to that of Figure 6 showing a sheet metal blank for the formation of yet another embodiment of the present invention.

Figure 18 represents a perspective view similar to that of Figure 2 of the embodiment indicated in Figure 17.

One form or embodiment of the present invention is illustrated in Figures 1 to 10 inclusive, the formation of which is illustrated in Figures 6 to 10 inclusive.

Thus, in this embodiment of the present invention, a flat sheet-metal strip 28 of suitable thickness having an aggregate width 21, is cut out in the general manner indicated in Figure 6, to form juxtaposed upper and lower generally sector-shaped cylinder contacting elements 22 and 23 with intervening connecting spacer portions 24 and with spring-forming portions 25.

The connecting spacer portions 24 may be perforated by providing openings 26 therein for oil drainage through the piston ring after it is finally formed, such apertures being advantageous when the piston ring is used for oil control purposes in one or two of the lower ring-receiving grooves 21 of a three-groove piston such as illustrated in Figure 5, or of a four-groove piston wherein the lowermost or the lower two ring-receiving grooves are provided with oil drain holes 28 extending through the piston wall 29 for oil draining purposes. When used for compression purposes in the uppermost ring-receiving groove 30 of the piston 31 or in the upper two ring-receiving grooves 30 and 32 (Figure 5), the holes 26 may be omitted although they may also be retained when the piston ring is for such compression purposes in the upper ring-receiving grooves.

In addition to cutting out the metal in the spaces 33 and 34 intervening the cylinder-contacting elements 22 and 23 respectively, the cylinder-contacting elements 22 and 23 are also preferably partly severed from the connecting spacer portions 24 by fracturing the metal along lines 35 and 36 more or less parallel to or in line with the edges 37 and 38 from the corners 39 and 40; to a suitable extent so that the spring-forming portions 25 of the sheet metal strip 28 may be more freely formed into the generally U-shaped springs 51 without interference from or binding by the cylinder-contacting elements 22 and 23.

The longitudinal or circumferential width of the cylinder-contacting portions 22 and 23 is slightly smaller in the base dimension 42 than in the end or peripheral dimension 43, this difference being so calculated that when the cylinder-contacting elements 22 and 23 have been bent over and have been brought generally edge to edge as indicated in Figures 1 and 2 and 10, the juxtaposed edges 44 and 45 will parallel each other and will be disposed as radii in relation to the axis or centre 46 of the piston.

The peripheral or cylinder-contacting edges or surfaces 47 and 48 of the cylinder-contacting elements 22 and 23, respectively, may also be

given a slight convex arcuate curvature between the ends 49 and 50 thereof corresponding to the curvature of the cylinder in which the piston ring is intended to be used, so that when the cylinder-contacting elements 22 and 23 are placed side by side in close proximity as indicated in Figures 1, 2, and 10, the successive adjacent cylinder-contacting surfaces 47 and 48, respectively, will form corresponding true circles matching the circle of the cylinder.

The formation of the blanks shown in Figure 6 may be accomplished by punching operations on any suitable punch press, either manual or semi-automatic or fully automatic, with suitable dies and punches either by step-by-step or progressive punching operations. However, if desired, the blanks shown in Figure 6 may also be formed by milling out the portions 33 and 34 or by cutting out the portions 33 and 34 on a shaper or on a broaching machine. If the portions 33 and 34 are to be cut out on a milling machine or on a shaper or on a broaching machine, several sets may be stacked together and may be milled, shaped or broached all together, gang-wise.

The piston ring is formed by bending over towards each other the juxtaposed cylinder-contacting elements 22 and 23 so that they more or less parallel each other as indicated in Figures 7, 8, 9 and 10, and also in Figures 2 and 3 and by corrugating or bending the spring-forming elements 25 in a generally radial direction to form a series of spaced corrugation-like or loop-like springs 51 of an axial dimension 42 generally corresponding to the distance between the inner flat surfaces of the cylinder-contacting elements 22 and 23 when bent into their final form as indicated in Figures 3 and 2.

In its final form, the piston ring thus formed will consist of a central corrugated annulus of alternating flattened crests 24 and rounded troughs 51, the crests 24 being radially outermost and having openings 26 therein, and a pair of integrally formed and substantially parallel cylinder-contacting elements 22 and 23 projecting radially outwardly from each crest 24.

The formation of the piston ring from the blank shown in Figure 6 may be accomplished by successive bending operations performed in any suitable sequence or all the bending operations may be done more or less simultaneously to produce the result indicated in Figures 9, 10, 1 and 2. In Figures 7, 8, 9 and 10, however, I have illustrated what may be one desirable sequence of bending or forming operations, although it is to be understood that this sequence may be changed, or the bending or forming operations may all be accomplished more or less simultaneously by suitable automatic or semi-automatic bending and forming jigs or fixtures or machines.

Thus, for instance, in Figures 7 and 8, I have illustrated what may be an initial stage in the formation of the piston ring wherein the cylinder-contacting elements 22 and 23 have been bent over to parallel each other and wherein the spring-forming portions 25 have been bent into an initial U-shape formation 52 preliminary to their formation into the more close loop-shaped spring 51 shown in Figures 9 and 10. In this condition, the piston ring forming strip would be generally straight as indicated particularly in Figure 8, with the juxtaposed edges 44 and 45 substantially separated from each other and in non-parallel relation. Thereafter, the generally U-shaped formations 52 may be collapsed somewhat to form the more or less loop-like springs

51 with a relatively smaller gap 53 between their free ends 54 and 55; the gap 53 being sufficient, however, so that the ends 54 and 55 will not quite touch each other when the juxtaposed radial edges 44 and 45 of the cylinder-contacting elements 22 and 23 have actually contacted each other. By this final collapsing operation the piston ring material or strip is formed into a generally arcuate shape indicated in Figure 10 generally corresponding to the curvature of the 10 cylinder in which the piston ring is to be used.

In the commercial manufacture of piston rings according to the present invention, the blank shown in Figure 6 as well as the corresponding piston ring strips shown in Figures 7, 8, 9 and 10 may be formed more or less continuously in relatively great lengths from which smaller pieces may then be cut off after the strip has been completely formed or shaped into the form shown in Figures 7 and 8, or even after it has been formed into the curved shape shown in Figures 9 and 10. The length of the individual pieces would correspond more or less accurately to the circumferential dimension of the piston ring desired. For the different size piston rings the other dimensions would also be varied to accord with the width of the ring-receiving groove, the depth of the ring-receiving groove, and diameter of the piston.

Thus, for instance, the individual pieces corresponding to the circumferential length of the piston ring could be cut off while the strip is straight as in Figures 7 and 8 and then the shorter piece curved and completed to the form shown in Figures 9 and 10 and in Figures 1 and 2, or the strip can be curved while it is still part of the whole piece of considerable length and formed into a generally spiral formation as it is being curved and thereafter individual pieces cut off corresponding to the circumferential length of the piston ring so that each piece will be one complete circle of the desired diameter.

In making the piston ring, the springs 51 or the corrugations are collapsed until the juxtaposed edges 44 meet each other or abut each other and until the edges 45 likewise meet and abut each other, thereby producing the curved shape. However, when the compression pressure is released the springs 51 or corrugations open up slightly or spring back slightly so that the edges 44 and 45 separate from each other slightly as indicated in Figures 2, 9 and 10. However, the circumferential length of the piston ring is so adjusted that when the free ends 56 and 57 of the piston ring abut each other and the ring is compressed circumferentially or tangentially into the diameter of the cylinder 58, the radial edges 44 and 45 of the cylinder-contacting elements 22 and 23, respectively, will generally abut each other or will have but a very small clearance between them. It is estimated that the total or aggregate of all clearances between the successive pairs of edges 44 in the entire circumference or between the successive pairs of edges 45 in the entire circumference may be a few thousandths of an inch, perhaps .003" to .007", more or less (that is, an amount perhaps no greater than the clearance at the gap in an ordinary piston ring; it being understood that at the gap or break 68 there would be substantially no clearance as the edges 56 and 57 will abut each other. Thus, by reason of the fact that each of the bends or corrugations or springs 51 tends to open up slightly when the ring is compressed into the cylinder as is indicated in Fig-

ure 1, there is a uniformly distributed tangential or circumferential force between successive sections of the piston ring, that is, between successive or adjacent cylinder-contacting elements 22 and 23, respectively, and this force is in turn translated into an outward radial component force tending to press the cylinder-contacting edges 47 and 48 thereof, into contact with the cylinder wall with a uniformly distributed and predetermined radial force.

The cylinder-contacting elements 22 and 23 are preferably (though not necessarily) staggered slightly or offset slightly in relation to each other as indicated particularly in Figures 6, 7, 8, 9 and 10, so that the edges 44 and edges 45 are not directly in alignment with each other but are slightly offset in relation to each other, thereby tending to minimize even any tendency to "blow-by."

In the manufacture of the piston ring of the present invention, I may also grind-finish the cylindrical periphery 59 of the completed ring by clamping the finished ring axially between suitable supporting discs upon a suitable mandrel or any suitable fixture, while the ring is generally fully compressed, and then grinding the periphery 59 to match the cylinder, by rotating the ring about its axis against a revolving grinding wheel. If desired, a number of piston rings may be so clamped and held side by side on the same fixture or on the same mandrel between the same clamping discs or blades, so that they may be ground all together to match the cylinder.

The gap or break 58 in the piston ring may be formed through the pair of juxtaposed cylinder-contacting elements 22 and 23 as indicated in Figures 1 and 2.

The piston ring of the present invention is preferably made of sheet steel of suitable consistency or suitable hardness although it may be made of other sheet metals, such as sheet bronze or sheet brass or other suitable alloys, both ferrous and non-ferrous. If the piston ring is made out of sheet steel, it may be formed out of fully annealed sheet steel but one capable of being subsequently hardened and tempered to a suitable degree of hardness and also to impart a suitable degree of resiliency to the spring members or corrugations 51. Thus, for instance, the blank shown in Figure 6 may be formed while the metal is completely annealed and the formation shown in Figures 7 and 8 and even the formation shown in Figures 9 and 10 may be made while the metal is fully annealed, although these formations may also be formed with a certain amount of hardness set into the metal by suitable hardening and tempering. The final hardening and tempering, however, should preferably be done before the cylinder-contacting circumference of the completed ring is grind-finished or otherwise finished to the cylinder diameter.

Another embodiment of the present invention is shown in Figures 11 and 12 in which the central corrugated annulus is relatively narrower and in which the crests 24 are solid and more rounded and have a smaller circumferential dimension than the cylinder-contacting elements 22 and 23, notches 35a and 36a replacing slits 35 and 36.

Figures 13 and 14 show another embodiment in which the cylinder-contacting elements 22 and 23 are given a generally L-shaped configuration in the sheet metal blank shown in Figure 13 with the base of the L of the element 22 ex-

tending in the direction opposite that of the element 23 so that, in the final ring, as shown in Figure 14, the staggering of the cylinder-contacting elements 22 and 23 is much more accentuated than shown in Figures 2, 6, 7, 8, 9 and 10. This formation is especially effective in minimizing any tendency to "blow-by."

Figures 15 and 16 show another embodiment in which the members or troughs 51 are displaced from the center line of the strip 21. In this embodiment successive members 51 are placed alternately above and below the center line of the piston ring although many other arrangements are possible and are comprehended in the present invention.

In Figures 17 and 18 is shown another embodiment of the present invention in which a pair of relatively narrow, axially separated spring members or troughs 51a and 51b are used. It is understood however that three or more of such similar members can be used and that the members 51a and 51b need not be parallel or placed in the relative positions shown.

In any of the embodiments shown, it is possible to make one of the cylinder-contacting elements 22 or 23 with a radially smaller dimension or to omit it completely. In such a case, each piston ring would present only a single narrow annular rib making contact with the cylinder; the spring-members 51 then acting as a supporting ring and spacing ring.

The piston ring of the present invention is highly effective both for oil control and for compression, and may be used without any separate expander spring and will produce a suitably high cylinder-contact pressure per unit of area between the cylinder-contacting surfaces of the piston ring and the cylinder wall, without, however, producing an excessive pressure which will result in a scoring of the cylinder wall.

The present invention may be embodied in other specific forms without departing from the spirit or essential attributes thereof, and it is therefore desired that the present embodiments be considered in all respects as illustrative and not restrictive, reference being had to the appended claims rather than to the foregoing description to indicate the scope of the invention.

Having thus described the invention, what is hereby claimed as new and desired to be secured by Letters Patent is:

1. A one-piece, flexible, circumferentially-expanding folded sheet-metal piston ring comprising a central, corrugated annulus composed of alternating crests and troughs of spring sheet metal, with the direction from crest to trough being generally radial, said troughs being radially innermost in relation to the crests and being continuously curved in cross-section at their bottoms, and said crests being radially outermost in relation to said troughs, a pair of more or less parallel integrally formed extensions projecting from each of said crests radially outwardly therefrom, said extensions being arranged in close proximity to each other to form a pair of more or less continuous, annular, axially displaced, cylinder-contacting ribs, said troughs being relatively narrow spring members axially displaced from the center plane of said ring.

2. A one-piece, flexible, circumferentially-expanding folded sheet-metal piston ring comprising a series of sections each consisting of top and

bottom walls and a back wall and generally sinusous loops of spring metal connecting the side edges of adjacent back walls, said loops projecting radially inwardly from said sections and being of an axial width not more than two-thirds the axial width of the piston ring, and said spring loops being displaced from the central plane of the piston ring.

3. A one-piece, flexible, circumferentially-expanding folded sheet-metal piston ring comprising a central, corrugated annulus composed of alternating crests and troughs of spring sheet metal, with the direction from crest to trough being generally radial, said troughs being radially innermost in relation to the crests and being continuously curved in cross-section at their bottoms, and said crests being radially outermost in relation to said troughs, a pair of more or less parallel integrally formed extensions projecting from each of said crests radially outwardly therefrom, said extensions being arranged in close proximity to each other to form a pair of more or less continuous, annular, axially displaced, cylinder-contacting ribs, said troughs being relatively narrow spring members axially displaced from the center plane of said ring, successive spring members being alternately above and below the center plane of said ring.

4. A one-piece, flexible, circumferentially-expanding folded sheet-metal piston ring comprising a series of sections each consisting of top and bottom walls and a back wall and generally sinusous loops of spring metal connecting the side edges of adjacent back walls, said loops projecting radially inwardly from said sections and being of an axial width not more than two-thirds the axial width of the piston ring, and said spring loops being displaced from the central plane of the piston ring, successive spring loops being alternately above and below the center plane of said ring.

5. A one-piece, flexible, circumferentially-expanding folded sheet-metal piston ring comprising a central, corrugated annulus composed of alternating crests and troughs of spring sheet metal, with the direction from crest to trough being generally radial, said troughs being radially innermost in relation to the crests and being continuously curved in cross-section at their bottoms, and said crests being radially outermost in relation to said troughs, a pair of more or less parallel integrally formed extensions projecting from each of said crests radially outwardly therefrom, said extensions being arranged in close proximity to each other to form a pair of more or less continuous, annular, axially displaced, cylinder-contacting ribs, said troughs being relatively narrow axially-separated twin spring members axially displaced from the center plane of said ring.

6. A one-piece, flexible, circumferentially-expanding folded sheet-metal piston ring comprising a series of sections each consisting of top and bottom walls and a back wall and generally sinusous axially-separated twin loops of spring metal connecting the side edges of adjacent back walls, said loops projecting radially inwardly from said sections and being of an axial width not more than two-thirds the axial width of the piston ring, and said spring loops being displaced from the central plane of the piston ring.

CARL F. ENGELHARDT.
